ATTORNEY'S

UNITED STATES PATENT OFFICE

ROBERT T. HAZELTON, OF CINCINNATI, OHIO, ASSIGNOR TO THE CINCINNATI SHAPER COMPANY, OF CINCINNATI, OHIO, A CORPORATION OF OHIO

PRESS BRAKE

Application filed October 23, 1926. Serial No. 143,759.

My invention relates to the structure of press brakes of improved structural characteristics more particularly related to heavy duty brakes having a minimum of cumbersome frame parts.

There has been devised by me in the past a type of heavy duty press brakes in which the housings were formed of double steel plates bolted over intermediate cores, with overhanging portions of the plates serving to provide the centers on which the operating shaft for the ram was given a bearing. This enabled me to bring the line of thrust of the eccentrics on the ram in a line parallel to and central of the vertical plane of the housings. In the present invention, my main object is to accomplish a like purpose, using a single plate for a housing. This device is shown and described in my United States Patent No. 1,618,825, dated February 22, 1927.

In the press brakes of the past, with which I am familiar, a heavy cross member is mounted across the tops of the housings and the thrust as applied to the ram is taken up by the cross member. Such a heavy and cumbersome construction is avoided in both my older form of brake and the one forming the basis for this specification.

In order to eliminate an operating shaft of large diameter, I so arrange the bearings and eccentrics that the shaft itself moves through an eccentric path while it is rotating, thus adding to the effect of the eccentrics and cutting down requirements as to size of parts, as will be more particularly explained.

In order to conserve heaviness of metal used, I prevent localization of strains by developing the necessary angles in the framework, ram and bed into curves. While as a principle of engineering, this effect is known and calculations can be based thereon, I am not aware of anyone having devised a structure particularly in press brakes, where its application can be made to serve the duty of conservation.

I have provided a simple and effective ram operating device, and in arrangements for application of power and adjustment of the ram, have improved over present day press brakes which have come to my attention.

I accomplish my several objects by that certain construction and arrangement of parts to be hereinafter more specifically pointed out and claimed.

In the drawings:

Figure 1 is a front elevation of the device.

Figure 2 is a central vertical section thereof.

Figure 3 is a detail side elevation of the frame, bed and ram, with parts broken away showing the ball and socket-like device for avoiding the developing of localized strains.

Figure 4 is a similar view taken in front elevation of the same parts.

Figure 5 is a section taken centrally and vertically through one of the ram operating devices, viewing same from the side of the machine.

Figure 6 is a like view viewing the parts as in Figure 5 from the front of the machine.

Figure 7 is a side elevation of one of the eccentric sleeves.

Figure 8 is a plan thereof.

Figure 9 is a like view to Figure 7, of the eccentric sleeve on the other housing.

Figure 10 is a plan view of the eccentric sleeve of Figure 9.

In the particular machine illustrated for the purpose of explaining my invention, I show the housings at 1, each consisting of a single steel plate, suitably supported on the floor or base. They can be made of composite plates or unitary cast steel members, as desired. The power input may be provided by means of a pulley 2, which drives a shaft 3. On the opposite side of the machine from the pulley, the shaft is equipped with a pinion 4, which drives the large gear 5.

The large gear 5 is located on the shaft 6, which carries the eccentrics that operate the

ram 7. The ram is a heavy steel plate, deeper at the center than at the edges, so that the power can be applied thereto at the edges with the maximum stiffness of the ram at the point 5 between the points of application of force. It is guided and held to ways 7^a on the faces of the housings in any accepted manner.

Boxes 8 are secured to the ram, which provide ball sockets for the balls 9 of the ram. 10 The balls rest against plates 10 in the sockets, and are held down by socket plates 11, which are held down by shouldered nuts 11^a, that screw down into the sockets over the tops of the balls. The nuts are held in place by 15 means of small plates 12. These plates slide in notches 13 in the sides of the box, and are held in clamping relation by means of screws 14, which pass through the slots 15 in the plates.

20 The parts above described are referred to in the plural, because there is one at each side of the machine, the two being alike.

The pitmen which carry the thrust balls are formed as bifurcated members with a 25 central depending tubular portion 16, within which is a screw 17. The screws carry the balls 9 integrally on their ends, and the screws are threaded into the tubular portions for purposes of adjustment of ram position. To 30 revolve the screws and thus change the position of the ram with relation to the eccentrics which operate the pitmen, journal boxes 17^a are set over the screws and support the cross shaft 18, that extends from pitman to pitman. 35 Within the journal boxes are screws 19 which engage worm gears 20, that are keyed to the lower ends of the screws, above the balls. The journal boxes have portions 21 which house the gears, and the boxes are held against 40 movement by being set over the gears, as shown more particularly in Figure 5.

The most important feature of the structure of the pitmen is that they are bifurcated. The single steel plate housings have the over- 45 hanging upper ends 22, and the two arms of the pitman structure as indicated at 23, are located one on each side of this overhanging portion, in such a way that the screws and balls depend in the plane of the housings and 50 in a substantially vertical plane.

The balls thus being in the plane of the housings, and the thrust thereon being in the same plane, avoids torsional strains on the housings, and avoids the necessity of a heavy 55 cross beam connecting the two housings at the top.

Figures 5 to 10 show most graphically the mode of mounting the shaft 6, which operates the two pitmen. Holes are formed in the 60 portions 22 of the single plate housings, in which are the bushings 24. The eccentric sleeves for the right hand end of the machine viewed as in Figure 1, are shown in Figures 5 and 8. The sleeves having triangular key 65 keys 25 and the shaft-like key ways 26, and

suitable rectangular keys 27, both keys and ways being slightly tapered, are driven between them, to key the sleeves to the shaft. Otherwise the sleeves can be shrunk or keyed in any other way to the shaft 6. Also, the 70 shaft 6 could be omitted and the drive at the left side of the machine duplicated at the right.

The right hand eccentric sleeve has the two portions 28 and 29 which are located on each side of the housing bushing, and are eccentrics which are held in the bifurcated ends of the pitmen, as by the top plates 30 secured down over the recessed upper ends 31 of the pitman arms. The central portion 32 of the sleeve is set within the housing bushing, and is eccentric to the center of the shaft 6. As a result of this structure, when the shaft is revolved by the gearing already briefly described, it moves through an eccentric path, 85 which adds to the eccentricity of movement of the eccentrics, thus avoiding the use of a very large and heavy shaft, which would otherwise be required in order to give enough metal in the sleeves and still provide for 90 proper length of stroke of the ram.

The sleeve on the other side has four portions instead of three. The portions marked 28^a and 29^a are alike to portions 28 and 29 of the sleeve firstly described, and the 95 portion 32^a is like the portion 32 of the first sleeve. The portion 33 of this left hand sleeve is developed on the true center of the central portions 32^a of the sleeve, and is keyed to the gear 5, which has been described.

Thus the gear 5 does not have to move in an eccentric path, while the shaft does have to, and the structure makes for lightness and efficiency as will be obvious.

Instead of mounting the ram ball boxes in 105 such a way as to subject the ram to a shearing strain, localized at the reduced end portions, I take particular care to avoid this. The boxes which have been referred to, are parts of plates 33 secured to the reduced ends of 110 the ram in such a way that a curved lower face 34 of each box rests on a curved exposed upper edge 35 of the ram ends (Fig. 4).

The bed of the ram is formed of a heavy metal plate 36, which in this instance is the 115 counterpart in shape, substantially to the ram only inverted. Thus it has the reduced lateral ends 37, and the deep central portion 38. The ends of the bed rest on projections 39 of the housing plates, one at each side of 120 the machine (Fig. 1 and Figs. 3 and 4). It is also held in place by bolting it to the housings in any desired way.

The bed is formed with a curved wall 40 at the lower edge of the portion 37, and the 125 housing plate is formed with a curved socket 41 at the upper edge of each shoulder, the curves being at right angles to each other. Shoes 42 are used to rest between the housing plate shoulders and the ends of the bed. These 130

shoes are held in place by the parts between which they lie, and have a curved lower surface 43, to match the curve of the housing shoulders, and a curved top surface at right angles as at 44, to match the curves of the bed ends.

In both instances I have provided a bearing between the relatively supported parts, that distributes the strain applied in doing work over a wide area of the parts affected, which would not be the case were the bearing faces formed with right angles instead of curves. Roughly speaking, this is because there is no reduced cross section caused by a corner, where the metal is weakest and where strains localize.

The various expedients and structural elements referred to are all directed to the end of permitting the use of single plate housings without heavy cross beams or heads, and this permits of a less cumbersome, and more powerful press brake structure of extreme rigidity in use, and simple to set up. It can be shipped knocked down with considerable 25 of its mechanism in place on each housing, and the parts readily assembled on the floor, which is not practical with housings that are connected across the top, and in which the force applied to the ram is directed along 30 lines which lie inside of the vertical planes of the housings, as has been prior practice.

Having thus described my invention what I claim as new and desire to secure by Letters Patent is:—

35 1. In a press brake the combination of housing means, a bed supported with relation thereto, and a ram supported thereon and movable with relation thereto, and means for applying pressure to the ram comprising an element moving in the vertical plane of the housing means, and having a bifurcated end to which force is applied and straddling said housing means, and means for applying said force, the same being mounted in the housing.

40 2. In a press brake the combination of housings, a bed supported with relation thereto, and a ram supported thereon and movable with relation thereto, and means for applying pressure to the ram comprising elements moving in the vertical plane of the housings, and having bifurcated ends to which force is applied and straddling said housings, and means for applying said force, the same being mounted in the housings, said housings being formed of individual plates of 45 steel.

3. In a press brake the combination of a pair of housings formed as individual plates of steel, a ram, eccentrics mounted in the housings in pairs, one on each side of each housing, and elements mounted over the eccentrics, and having means thereon for engaging the ram.

45 4. In a press brake the combination of a

pair of housings formed as individual plates of steel, eccentrics mounted in the housings in pairs, one on each side of each housing, and elements mounted over the eccentrics, and having means thereon for engaging a ram, and a ram mounted to move vertically on said housings, said elements having members thereon to engage the ram along a line within the vertical plane of the housings.

5. In a press brake the combination of a pair of housings formed as individual plates of steel, eccentrics mounted in the housings in pairs, one on each side of each housing, and elements mounted over the eccentrics, and having means thereon for engaging a ram, and a ram mounted to move vertically on said housings, said elements having members thereon to engage the ram along a line within the vertical plane of the housings, said housings having overhanging portions in which the eccentrics are mounted whereby the elements apply force to the ram in substantially the line of movement of the ram.

6. In combination in a press brake, a pair of housings having sleeves set therein having at least one exposed eccentric, pitmen for operating the ram of the brake, set over the eccentrics, a driving shaft coupling the sleeves in the housings, and secured fast to said sleeves, and said sleeves in the portions set within the housings formed eccentric to the shaft, and means for revolving the eccentric structure, whereby said shaft passes through an eccentric path during revolution.

7. In combination in a press brake, a pair of housings having sleeves set therein having at least one exposed eccentric, pitmen for operating the ram of the brake, set over the eccentrics, a driving shaft coupling the sleeves in the housings, and secured fast to said sleeves, and said sleeves in the portions set within the housings formed eccentric to the shaft, and means for revolving the eccentric structure, whereby said shaft passes through an eccentric path during revolution, said driving means having an element to be rotated, and means on one of the sleeves at least, and co-axial with the portions of said sleeve that lies within the housing on which said element is mounted.

8. In a press brake the combination of a supporting housing and a bed rigidly secured thereto, and bearings intermediate the bed and housing, comprising shoulders on the respective parts, and said shoulders arranged to have each a radius of curvature at the point of support, whereby strains on the housing and bed are not localized.

9. In a press brake the combination of a supporting housing and a bed rigidly secured thereto, and bearings intermediate the bed and housing comprising shoulders on the respective parts, and said shoulders arranged to have each a radius of curvature at the point of support, for the purpose described, and a

filler piece between the parts at said point of support, having matching radii of curvature.

10. In a press brake the combination of a supporting housing and a bed, bearings intermediate the bed and housing comprising shoulders on the respective parts and said shoulders arranged to have each a radius of curvature at the point of support, for the purpose described, and a filler piece between the parts at said point of support, having matching curved surfaces, the radii of some of the surfaces being at right angles to each other.

15. 11. In a press brake the combination of a supporting housing and a bed comprising shoulders on the respective parts, and said shoulders arranged to have each a radius of curvature at the point of support, for the purpose described, and a filler piece between the parts at said point of support, having matching radii of curvature, said matching curved surfaces, the radii of some of the surfaces being at right angles to each other.

20. 25. 12. In a press brake, a frame, and a ram moving along the frame, and means supported by the frame and engaging the ram to operate it, said ram having a curved edge where the force is applied in its operation, and a member secured to the ram and directly receiving the applied force, said member having also a curved edge where it engages the ram.

30. 35. 13. In a press brake the combination of housings, a bed supported with relation thereto, a ram supported on and movable along the housings, and means supported in the housings and engaging the ram, by which means force is applied to the ram to move it with relation to the housing, said means having elements thereof located on each side of each housing in such a position as to balance the load exerted against the housings.

40. 45. 50. 14. In a press brake the combination of a housing, a bed supported with relation thereto, a ram movable along the housing, and means supported in the housing and engaging the ram, by which means force is applied to the ram to move it with relation to the housing, said means having elements thereof located on each side of the housing in such a position as to balance the load exerted against the housing.

55. 60. 15. In combination in a press brake, a housing, a ram movable along the housing, and means for applying moving force to the ram, comprising an element mounted in the housing, rotary means on a fixed axis to revolve said element, the mounting thereof in the housing being concentric with the rotary means, and a pair of eccentrics developed on said element, and means on the ram engaging said eccentrics and operated thereby.

65. 16. In a press brake the combination of a supporting housing and a bed rigidly secured

thereto, the respective parts having shoulders, a filler piece secured between said shoulders, one of the surfaces of said filler piece at least having a curved contour, and the shoulder against which said surface abuts having a matching curved contour whereby strains are not localized.

70. 75. 17. In a press brake the combination of supporting housings and a bed, shoulders on the supporting housings against which the bed is to be mounted, said shoulders having a curved contour, a curved portion serving as a shoulder at the ends of the bed matching in curvature the surface of the housing shoulders, and means for rigidly securing the bed to the housing.
